UNITED STATES PATENT OFFICE.

MAYME J. PEPPARD, OF MINNEAPOLIS, MINNESOTA.

TRUNK.

1,106,581.

Specification of Letters Patent. Patented Aug. 11, 1914.

Application filed July 23, 1909, Serial No. 509,196. Renewed March 1, 1913. Serial No. 751,644.

To all whom it may concern:

Be it known that I, MAYME J. PEPPARD, of Minneapolis, Hennepin county, Minnesota, have invented certain new and useful 5 Improvements in Trunks, of which the following is a specification.

My invention relates to trunks for travelers' use and particularly to that type, which are capable of being utilized as a combined 10 wardrobe and chiffonnier at the end of the 10 journey.

The object of my invention is to provide a trunk of strong durable construction and one which can be easily and quickly adapted 15 for an article of room furniture.

A further object is to provide a trunk, which when set up in the room for use as a wardrobe and chiffonnier, will present a neat, ornamental appearance and be devoid 20 of projecting parts usually incident to trunks of this type.

A further object is to provide a wardrobe adjunct to the trunk which, when the trunk is in use as a chiffonnier, will be included 25 entirely within the walls of the trunk.

Other objects of the invention will appear from the following detailed description.

My invention consists generally in various 30 constructions and combinations, all as hereinafter described and particularly pointed out in the claims.

In the accompanying drawings, forming part of this specification, Figure 1 is a perspective view of a trunk embodying my invention parts being broken away, opened up and ready for use, Fig. 2 is a similar view showing the cover of the trunk closed with the wardrobe door open.

40 In the drawing, 2 represents a side wall of the trunk 3 a lower section of the cover and 4 the upper section, the former being hinged to one of the side walls and adapted to swing back against said wall when the 45 trunk is stood on end and opened up. The upper section 4, of the cover is secured to an end section 5, which is formed by dividing the end of the trunk transversely through the middle thereof and said section 5 is 50 hinged at 6 to the other end section 7, which is rigidly secured to the trunk walls. The cover section 4 and the end section 5 being secured together, it follows that when the cover is lifted and swung back to the position shown in Fig. 1, a flat top 8 will be 55 formed on which toilet articles may be

placed. A mirror 9 may be secured to the cover section and drawers 10 fitting within the section 5 and exposed when the section is raised, a flexible flap 11 depending beneath 60 the drawers and concealing the hinge connection between the sections 5 and 7.

I prefer to provide a partition 12 extending longitudinally of the trunk and dividing it into a forward and rear compartment and 65 also serving to stiffen the end sections 5 and 7. The rear compartment 13 is adapted for use as a wardrobe, and in the forward compartment 14 a series of drawers 15, 16, 17, 18, and 19 are arranged, one above another, 70 the drawers being held in place between the partition 12 and the cover sections when the trunk is closed. The drawers may be made in various sizes, according to the needs of the traveler, and when the trunk is set 75 up in a room and opened it will present a neat, ornamental appearance and form an article of furniture. This is due to the fact, particularly, that the wardrobe feature remains included within the walls of the trunk, 80 even when it is set up on end and used as a chiffonnier. A door 20 is preferably provided for the wardrobe chamber, hinged on one side and secured by a lock 21. When this door is closed the wardrobe and cloth- 85 ing therein will be concealed and although at hand for immediate use, will not be visible and scattered around the trunk, as is usually the case in wardrobe trunks of ordinary construction. The user of the chiffon- 90 nier will have the wardrobe close at hand and will also be convenient to the chiffonnier drawers and the looking glass.

I do not wish to confine myself to the details of construction, as they may be modified in various ways by anyone skilled in the art.

The trunk may be made in various sizes and suitably ironed and strengthened at the corners, as usual in articles of this kind. 100

I claim as my invention:—

1. A chiffonnier trunk comprising side and end walls, one of said end walls forming the lower end of the trunk when it is used as a chiffonnier, a cover divided transversely into 105 an upper and a lower section, the upper end of the trunk being divided transversely into a rigid and a movable section hinged together, the upper cover section being rigidly secured to said movable section and adapted 110 to swing upwardly therewith and rest upon said rigid section, a partition extending

lengthwise through said trunk from end to end thereof and between said rigid and movable end sections and bracing the same, the space on one side of said partition forming a wardrobe, the wall of the trunk having a door leading thereto, and a series of drawers arranged one above another in the space on the other side of said partition and exposed when said cover is raised, substantially 10 as described.

2. A chiffonnier trunk comprising side and end walls, one of said end walls forming the bottom of the trunk when it is used as a chiffonnier, the other end of the trunk being divided transversely into a rigid and a movable section hinged together, a cover rigidly secured at one end to said movable section and adapted to swing upwardly therewith and rest upon said rigid section, a shelf 20 arranged beneath the movable section of said end and extending from the front of the trunk to the rigid section of said end, a partition dividing the trunk vertically and extending to said rigid and movable sections, said partition being located intermediate to the front and rear of said chiffonnier and dividing the space within the trunk into vertical compartments, the compartment on one side of said partition forming a vertical 25 wardrobe and having a suitable door and a series of drawers fitting into the compartment.

ment on the other side of said partition beneath said shelf and concealed when the trunk cover is closed.

3. A chiffonnier trunk comprising side and end walls, one of said end walls forming the bottom of the trunk when used as a chiffonnier, the other end of the trunk being divided transversely into a rigid and a movable section hinged together, the body portion 35 of the trunk having a wardrobe compartment under the rigid section of the end and provided with a series of drawers at one side thereof to lie below the hinged section of the end when closed, the wardrobe compartment being formed with an opening to the rear of the drawers in the wall at which the ends of the drawers lie and provided with a door for the opening and which forms a portion of that wall of the body, 40 and a cover secured at one end to the movable section of the end portion and adapted to swing upwardly therewith and with said movable section to rest above the wardrobe compartment when the trunk is set upon 45 end, substantially as described.

In witness whereof, I have hereunto set my hand this 16th day of July 1909.

MAYME J. PEPPARD.
